United States Patent

Des. 240,748

Patented July 27, 1976

240,748

GOLF CLUB HEAD

Robert E. Bock, Prospect, Conn., assignor to O. F. Mossberg & Sons, Inc., North Haven, Conn.

Continuation-in-part of abandoned design application Ser. No. 368,237, June 8, 1973. This application Sept. 3, 1974, Ser. No. 502,281

Term of patent 3½ years

Int. Cl. D21—02
U.S. Cl. D34—5 GH

FIG. 1 is a front elevational view of a golf club head showing my new design;

FIG. 2 is an end elevational view taken from the right of FIG. 1;

FIG. 3 is a rear elevational view;

FIG. 4 is an end elevational view taken from the left of FIG. 1;

FIG. 5 is a top plan view; and

FIG. 6 is a bottom plan view thereof.

This is a continuation-in-part of design application Ser. No. 368,237, filed June 8, 1973, now abandoned.

I claim:

The ornamental design for a golf club head, substantially as shown and described.
